CURVE SCRIBER

Victor Debs, Ridgewood, N. Y.

Application June 21, 1952, Serial No. 294,838

5 Claims. (Cl. 33—30)

1
This invention relates to a curve scribe, and more particularly to an instrument which will scribe a variety of mathematical or geometrical curves. The invention is especially useful in scribing ellipses, ovoid forms and spirals, to which uses, however, it is not restricted.

A variety of curve-scribing instruments have heretofore been designed and constructed, and some of such instruments have actually been put upon the market. However, such instruments have generally been complicated and expensive. They have also been delicate, difficult to adjust and to keep in adjustment; and they have been subject to inaccuracies due to entrance of the human equation into their operation.

I have now constructed a curve scribe which is simple, inexpensive and rugged. Adjustment of the instrument with respect to character and size of the curve to be scribed is easily and accurately made, and is retained with certainty. Furthermore, a scribe according to the invention is so constructed that the human equation enters to a minimum extent into its operation.

According to the invention, means is provided whereby the marking element of the scribe is maintained at all times in perpendicular position with respect to the surface upon which the curve is to be scribed. Furthermore, means is provided for insuring a constant and even pressure of the marking element upon this surface. Finally, the invention provides means which compensates any unevenness in tension which a user may apply to the scribe during its operation, thereby minimizing the effect of the human equation in using the instrument.

The invention contemplates other advantageous and novel features, as will appear from the present specification.

One form of the invention is shown by way of illustration in the accompanying drawings, in which—

Fig. 1 is an elevation, partly in section, illustrating a curve scribe constructed and arranged according to the invention, the curve scribe being set up to scribe an ellipse which is shown in perspective;

Fig. 2 is a longitudinal horizontal section of the curve scribe shown in Fig. 1, the section being taken on the line II—II of Fig. 1;

Fig. 3 is a vertical section taken on the line III—III of Fig. 1, viewed in the direction of the arrows, most of the apparatus appearing in elevation;

Fig. 4 is a perspective view of one of the specially-formed pins used with the curve scribe;

2
Fig. 5 is a perspective view of a pencil-bearing marking element for use as a part of the curve scribe;

Fig. 6 is a plan view illustrating the manner of using the curve scribe to scribe a curve of ovoid form; and

Fig. 7 is a plan view illustrating the manner of using the curve scribe to scribe a helical curve.

In the embodiment of the invention which is illustrated in Figs. 1, 2 and 3, there is shown a curve scribe 10, comprising a standard 11, a bracket 12 hinged to the standard, and a marking element holder 13 slidably carried by the bracket 12 for movement toward and away from the standard 11. A marking element 14 is reciprocably mounted in the marking element holder 13 for free vertical movement therein. Thus the standard 11 and the marking element 14 are swiveled with respect to each other by means of the bracket 12 and the marking element holder 13, and the slidable mounting of the holder in the bracket permits the standard and the marking element to be brought closer together or to be farther separated.

The standard 11 comprises a circular foot 15 having a plane annular lower surface 16 adapted to rest slidably upon a plane surface, as the upper surface of a piece of paper upon which the curve scribe 10 is used. A central concave portion 17 at the bottom of the foot 15 insures against wobbling of the foot when it rests upon the plane surface. A shaft 18 is fixed centrally in the foot 15 and extends perpendicularly therefrom when the foot rests upon a horizontal surface; and a sleeve 19 is closely fitted upon the shaft for rotation thereon. The bracket 12 is fixed to the sleeve 19, which hinges the former to the standard. Finally a handle 20 is fixed to the upper end of the shaft 18 beyond the sleeve 19 in order that the standard may be moved about on the horizontal surface.

The bracket 12 comprises two vertical parallel plates 21 and 22 integrally connected together by a web 23 across their upper edges. The parallel plates 21 and 22 are fixed to the sleeve 19 as by welds 24 and 25 respectively (see Fig. 2) and extend horizontally from the sleeve. Thus the bracket 12 is free to move with the sleeve 19 pivotally about the shaft 18. The plates 21 and 22 have parallel slots 26 and 27 therein extending longitudinally thereof at right angles to the axis of the sleeve 19 from points adjacent the welds 24 and 25 to the ends of the plates.

The marking element holder 13 comprises a tubular member 28 which is fixed to the end of

a forked member 29 as by welds 30 and 31. (See Fig. 2.) The forked member 29 has a pair of legs 32 and 33 which are separated by a sufficient distance to enable them to fit closely, but slidably between the plates 21 and 22 of the bracket 12. Furthermore, the legs 32 and 33 have slots 34 and 35 respectively therein which register with the slots 26 and 27 in the plates 21 and 22 respectively. However, the slots 34 and 35 are made wider than the slots 26 and 27 for a purpose which will later appear.

A pin 36 extends through the unslotted ends of the legs 32 and 33 remote from the holder 13, and fits slideably into the slots 26 and 27 in the plates 21 and 22 to guide the forked member 29 as it slides back and forth in the bracket 12. A second pin 37 of larger diameter than the pin 36 extends through suitably enlarged portions of the slots 26 and 27 in the plates 21 and 22 and also through the slots 34 and 35 in the forked member 29 for a purpose which will later appear. Split rings 38 and 39 snap in well known manner into circumferential grooves (not shown) in the second pin 37 immediately beyond the outer surfaces of the respective plates 21 and 22 to fix the second pin 37 in position during operation of the curve scribe. Thus the pins 36 and 37 constrain the forked member for motion at right angles to the shaft 18.

A helical compression spring 40 is disposed between the end of slots 34 and 35 of forked member 29 and the pin 37 in the space between the legs 32 and 33 of the forked member 29, the diameter of the spring being such as to cause a part thereof to extend partly into each of the slots 34 and 35, whereby the spring is steadied.

From the foregoing it will be evident that sliding movement of the forked member 29 in the bracket 12 away from the sleeve 19 will be resisted by the resiliency of the compression spring 40. Moreover, by removing the split rings 38 and 39 from second pin 37, that pin may be withdrawn, and the helical compression spring 40 released. The marking element holder 13 may thus be separated from the bracket 12.

The marking element 14 has a cylindrical stem 41 thereon which fits closely but slideably into the tubular member 28. A transverse pin 42 fixed in the stem 41 of the marking element extends outwardly through a longitudinal slot 43 in the tubular member 28 to prevent turning of the marking element in the tubular member; and a weak spring 44 is compressed within the tubular member between its closed top and the top of the stem 41 to urge the marking element gently out of the tubular member, that is to say downwardly. As here shown, the top of the tubular member comprises a threaded plug 45, whereby the force exerted by the weak spring upon the top of the cylindrical stem 41 may be adjusted. Accordingly, when the lower surface 16 of the circular foot 15 rests upon the paper or other surface upon which a curve is to be scribed, the marking element 14 will make suitable contact with the paper or surface, through the force of gravity and the gentle urging of the weak spring 44. Thus means is provided for insuring a constant and even pressure of the marking element upon the surface upon which the curve is being scribed.

The slot 43 has a transverse hooked extension 46 at its upper end thereby making it possible to move the marking element inwardly of the tubular member 28 against the resiliency of the weak spring 44 and, by turning the marking ele-

ment, to hold it upwardly in the holder 13 out of contact with the surface upon which it acts. In such inoperative position, there is no objection to having the marking element turned in the tubular member 28.

The curve scribe is operated in conjunction with a loop of thread in a manner later to be described. For this purpose a thread reel 47 is mounted upon a bracket 48 fixed in known or convenient manner to the tubular member 28 at the opposite side thereof from that bearing the welds 30 and 31. The bracket 48 is a forked member the legs of which extend away from the tubular member, each leg having a round opening 49 therein for reception of a split shaft 50 of the thread reel 47. A knurled head 51 at one end of the split shaft 50 provides means for turning the thread reel in the bracket 48. A looped thread 52 is wound about the split shaft 50 of the thread reel between the forks of the bracket 48 and extends thence through an opening 53 in a downwardly extending guide member 54 forming part of the holder 13. Passing along the guide member 54 the thread 52 passes through a terminal slot 55 at the lower end of the guide member 54, whence the looped thread extends horizontally away from the marking element 14 and the standard 11 to engage a plurality of double conical location elements 56 (see Fig. 4). The double conical location elements 56 are each formed with a central waist 57 and opposite terminal cone bases 58; and a pin 59 is positioned centrally of each terminal cone base 58 for insertion into the surface upon which the curve is to be scribed to position the location element thereon. The double conical elements 56 are so formed that, when positioned upon the surface upon which a curve is to be scribed, their central waists 57 will be at the elevation above the surface at which the standard 11 supports the terminal slot 55 of the guide member 54.

In the embodiment illustrated in Fig. 1 the curve scribe is shown as set up for scribing an ellipse, the marking element 14 being illustrated as a draftsman's pen. The curve scribe is used to describe an ellipse in the following manner:

Two of the double conical location elements 56 are positioned at the foci of the ellipse to be scribed. To this end a pin 59 of each element is thrust through the paper upon which the ellipse is to be drawn and into the drafting board beneath it until a terminal cone base 58 of each element rests evenly upon the upper surface of the paper. Thereupon the neck of the reversely conical location pins is at the elevation of the terminal slot 55 of the guide member 54 when the circular foot 15 of the standard 11 rests upon the same surface. The doubled or looped thread is next partially unwound from the thread reel 47, drawn a sufficient distance through the opening 53 and the terminal slot 55 in the guide member 54, and looped about the central waists 57 and 57 of the two double conical location elements 56 and 56. The marking element 14, which has been partly withdrawn into the tubular member 28, with its transverse pin 42 in the hooked extension 46 of the longitudinal slot 43, is now turned and allowed to move partly out of the tubular member. In effecting this, the transverse pin 42 slides in the longitudinal slot 43, and remaining in the longitudinal slot, prevents the marking element from turning in the tubular member. The scribing point of the marking element 14, as the marking end of the pen illustrated in Fig. 1, is now placed at one end of the major axis of the ellipse

to be scribed. Thereupon the knurled head 51 is turned to wind any slack in the thread 52 upon the split shaft 50 until the thread is pulled gently taut about the central waists 57, 57 of the double conical elements 56, 56 and through the terminal slot 55 of the guide member 54. In this condition the looped thread extends horizontally above the paper.

Grasping the handle 20, the standard 11 is drawn slightly away from the marking element holder 13, compressing the helical spring 40 to a limited extent. This is possible because the marking element holder is restrained by the tension of the thread 52 which is looped about the double conical elements 56. Maintaining substantially even tension in manipulating the handle 20, the standard 11 is moved completely around the two double conical location elements 56, 56, causing the marking element 14 to scribe the ellipse. The size and character of the ellipse is, of course, governed by the distance between the double conical elements and by the length of the looped thread between the farthest double conical element and the guide member 54.

The circular foot 15 and the shaft 18 extending vertically therefrom provide means whereby the marking element 14 is maintained at all times in perpendicular position with respect to the surface upon which the ellipse is scribed. Inaccuracies in scribing the ellipse which might result from holding the marking element at an angle to the vertical are thus avoided. Furthermore, the force of gravity upon the marking element 14, which is freely slidable in the vertically-positioned tubular member 28, plus the action of the weak spring 44 upon the marking element insures a constant and equal pressure of the marking element upon the surface on which the curve is being scribed. Finally the relationship of the marking element holder and the standard, together with the action of the compression spring 40, provides means which compensates any unevenness in tension which a user may apply to the scribe during its operation. Thus, little variation results in the tension applied to the looped thread 52, and the looped thread is not stretched. The effect of the human equation in using the instrument is accordingly minimized.

Instead of drawing the curve with a draftsman's pen as illustrated in Fig. 1 it may be desired to draw the curve in pencil. A marking element for this purpose is illustrated in Fig. 5, a pencil holder 60 of known form being there illustrated with a lead 61 releasably held therein. The same type of cylindrical stem 41 is fixed to the pencil holder 60 as is fixed to the pen illustrated in Fig. 1, and the same type of transverse pin 42 is fixed to the cylindrical stem 41 for the same purpose as that heretofore described.

Fig. 6 illustrates how the curve scribe may be employed to scribe the ovoid form there illustrated. For this purpose double conical location elements 56 are inserted at points A, B and C, which are spaced to provide the desired scribed form. The thread 52 is looped around the central waists 57 of these location elements, adjustment of the length of looped thread is made by turning the knurled head 51 and the standard 11 is moved around the location elements in order to scribe the ovoid form.

In Fig. 7 a method of scribing a spiral curve is illustrated. In this case four double conical location elements 56 are positioned at points W, X, Y and Z closely together. The thread 52 is looped over but one of the location elements, 75

and the length of the looped thread is suitably adjusted. The spiral is then scribed by giving the standard 11 a generally circular movement during which the looped thread winds progressively around the four location elements becoming shorter with each rotational movement. Alternatively, the looped thread 52 may be initially wound about the four location elements, and the spiral curve may be scribed as the thread is unwound from them. The result is a spiral curve such as that illustrated.

Obvious methods of scribing other curves may, of course, be employed.

From the foregoing it will be apparent that the present invention provides a simple, inexpensive and rugged curve scribe which is easily adjusted and used to scribe a variety of different curves. Because of the simplicity of its adjustment, that adjustment is retained without difficulty. Furthermore, the curve scribe minimizes the effect of the human equation in using the instrument.

The form of the invention here described and illustrated is presented merely as an example of how the invention may be embodied and applied. Other forms, coming within the proper scope of the appended claims, will readily suggest themselves to those skilled in the curve scribing art.

I claim:

1. A curve scribe comprising: a standard including a foot having a plane lower surface adapted to rest slidably upon the surface upon which a curve is to be scribed, and a shaft fixed to said foot and extending perpendicularly therefrom; a bracket hinged to said shaft, said bracket including two parallel plates; a marking element holder slidably connected to said bracket for motion at right angles to said shaft; a marking element slidable in said marking element holder in the direction in which said shaft extends to contact the surface upon which the curve is to be scribed with its scribing end; and a looped thread adjustably connected to said marking element holder for looped connection about a plurality of location elements to determine the changing position of said marking element while scribing a curve.

2. A curve scribe comprising: a standard including a foot having a plane lower surface adapted to rest slidably upon the surface upon which a curve is to be scribed, a shaft fixed to said foot and extending perpendicularly therefrom, and a sleeve closely fitted upon said shaft for rotation thereon; a bracket fixed to said sleeve, said bracket including two parallel plates; a marking element holder slidably connected to said bracket for motion at right angles to said shaft; a marking element slidable vertically in said marking element holder to contact the surface upon which the curve is to be scribed with its scribing end; and a looped thread adjustably connected to said marking element holder for looped connection about a plurality of location elements to determine the changing position of said marking element while scribing a curve.

3. A curve scribe comprising: a standard including a foot having a plane lower surface adapted to rest slidably upon the surface upon which a curve is to be scribed, a shaft fixed to said foot and extending perpendicularly therefrom, and a sleeve closely fitted upon said shaft for rotation thereon; a bracket fixed to said sleeve, said bracket including two parallel plates; a marking element holder slidably connected to said bracket for motion at right angles to said

shaft, said marking element holder including a vertical tubular member, a forked member fixed to said tubular member and spring-restrained between said parallel plates, and a thread reel; a marking element slidably vertically in said tubular member to contact the surface upon which the curve is to be scribed with its scribing end; and a looped thread adjustably connected to said thread reel for looped connection about a plurality of location elements to determine the changing position of said marking element while scribing a curve.

4. A curve scribe comprising: a standard including a foot having a plane lower surface adapted to rest slidably upon the surface upon which a curve is to be scribed; a bracket hinged to said standard to swing completely thereabout in fixed horizontal position; a marking element holder slidably connected to said bracket for motion at right angles to said standard, said marking element holder including a vertical tubular member, a thread reel, and a downwardly extending thread guiding member having an opening and a terminal slot therein; a marking element slidably vertically in the vertical tubular member of said marking element holder to contact the surface upon which the curve is to be scribed with its scribing end; and a looped thread connected to said thread reel and passing through the opening and the terminal slot in said thread guiding member for looped connection about a plurality of location elements to determine the changing position of said marking element while scribing a curve.

5. A curve scribe comprising: a standard including a foot having a plane lower surface

10

15

20
